(57) **CLAIM**

The ornamental design for an extension cord, as shown and described.

DESCRIPTION

FIG. 1 is a top, front perspective view of a first embodiment of an extension cord;

FIG. 2 is a front elevation view of the extension cord;

FIG. 3 is a right, side elevation view of the extension cord, the left side being a mirror image thereof;

FIG. 4 is a top plan view of the extension cord;

FIG. 5 is a bottom plan view of the extension cord;

FIG. 6 is a top, front perspective view of a second embodiment of an extension cord;

FIG. 7 is a right, side elevation view of the extension cord, the left side being a mirror image thereof;

FIG. 8 is a top plan view of the extension cord; and,

FIG. 9 is a bottom plan view of the extension cord.

In the drawings, the broken lines are for the purpose of illustrating portions of the electrical box that form no part of the claimed design. The extension cord is shown with a symbolic break in its length. The appearance of any portion of the article between the break lines forms no part of the claimed design.
